UNITED STATES PATENT OFFICE

153,584

DESIGN FOR AN AMPOULE SEALING DEVICE

John H. Brewer, Baltimore, Md., assignor to Hynson, Westcott & Dunning, Incorporated, Baltimore, Md., a corporation of Maryland

Application December 24, 1946, Serial No. 135,736

Term of patent 14 years

(Cl. D16—1)

To all whom it may concern:

Be it known that I, John H. Brewer, a citizen of the United States, residing at Baltimore, in the State of Maryland, have invented a new, original, and ornamental Design for an Ampoule Sealing Device, of which the following is a specification, reference being had to the accompanying drawings, forming part hereof, and wherein:

Fig. 1 is a perspective view of one side of an ampoule sealing device, showing my new design, and

Fig. 2 is a perspective view of the opposite side of the same, with the dotted line showing of the hose shown in Fig. 1 omitted for convenience of illustration.

The dominant features of my design reside in the portions shown in full lines.

I claim:

The ornamental design for an ampoule sealing device, substantially as shown and described.

JOHN H. BREWER.
